UNITED STATES PATENT OFFICE

2,550,194

IMITATION BRICK FORMING MOLD FOR
CONCRETE WALLS

Bert S. Jackson, Indianapolis, Ind.

Application August 18, 1949, Serial No. 110,945

3 Claims. (Cl. 25—118)

1

The present invention relates to new and useful improvements in stencils for finishing the walls of a building and more particularly to a stencil or marking a cement finishing surface of a wall to represent the bricks and mortar joints of a brick wall.

An important object of the invention is to provide a finishing stencil of this character including ribs on the inner surface of the stencil to match and fit in the imitation mortar joints of imitation brick building blocks to hold the stencil firmly against the wall while a finishing surface of cement is applied to the surface of the wall.

A further object of the invention is to provide a stencil of this character having a handle at its upper edge for holding the stencil against a wall, the upper and one side edge of the stencil being positioned forwardly of the plane of the stencil to prevent marring of the previously applied finishing cement and providing an adjustable stop pin or gauge at the upper edge of the stencil adjacent the handle to prevent tipping of the upper edge of the stencil inwardly by pressure applied to the handle.

A still further object is to provide a device of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a rear perspective view of the stencil;

Figure 2 is a front perspective view thereof; Figure 3 is a vertical sectional view, and

Figure 4 is a front elevational view of a modified stencil design.

Referring now to the drawings in detail, wherein for the purpose of illustration I have disclosed a preferred embodiment of the invention, the numeral 5 designates the stencil frame generally which is preferably constructed of light gauge sheet metal of rectangular form and formed with openings 6 separated by horizontal and vertical bars 7 and 8 substantially in the form of a grate construction to form the openings 6 of a size and shape corresponding to the size and shape of the exposed surface of the

2

bricks of a wall and with the bars 7 and 8 corresponding to the mortar joints of the wall.

The upper edge 9 and one side edge 10 of the stencil frame 5 are offset forwardly of the plane of the central portion of the stencil to form flanges positioned outwardly at the upper and side edge of the frame while the opposite side edge of the frame is formed with a forwardly extending flange 11.

10 A handle 12 is secured to the upper flange 9 in a forwardly projecting position.

The rear surface of horizontal and vertical bars 7 and 8 are formed with rounded ribs 13 while substantially sharp ribs 14 project rearwardly at the perimeter of openings 6.

The bars 7 and 8 form the openings 6 of a size and shape of a full brick as shown at 15 and of half bricks as shown at 16, the outer ends of the half brick openings 16 projecting outwardly beyond the outer ends of the full brick opening 15, and the marginal rib 14 is omitted from the outer end portions of the half brick openings 16 as shown at 14a in Figure 1 of the drawings.

25 The invention is used by placing the stencil frame 5 against the outer surface of a cement block wall 17 and with the ribs 13 and 14 positioned in the imitation mortar joints 18 on the outer surface of the block. A finishing coating of cement 19 of a suitable color is then spread over the surface of the stencil to work in the openings 15 and 16 to thus provide an imitation brick finish for the surface of the wall.

The flanges 9 and 10 space the stencil frame from the previously finished surface of the work to prevent marring thereof and the outwardly projecting ends of the half brick openings 16 which are free of ribs on their inner surfaces enable matching of the half brick openings as the stencil is advanced without a break in the finished surface.

35 The rounded ribs 13 and the sharpened ribs 14 prevent friction or suction in the mortar grooves 18 to avoid damage to the edges of the finished work.

40 A stop pin or thumb screw 4 is provided at the upper flange 9, adjacent handle 12 to enter one of the mortar grooves 13 to prevent tilting of the upper edge of the stencil by pressure applied to the handle.

45 In the operation of the device, the stencil frame 5 is placed against a building wall constructed of building blocks having imitation brick mortar joints 18 in the surface thereof and with the ribs 13 and 14 seated in the grooves. Cement

50

55

of a desired color is then spread over the outer surface of the stencil frame to work the cement into the openings 15 and 16 to form an imitation brick finish on the wall.

The raised flanges 9, 10 and 11 on the stencil frame prevent the finishing cement from spreading onto the previously finished portion of the wall as well as on the unfinished surface adjacent flange 11 and raised flanges 9 and 10 prevent contact of the stencil frame with the previously finished surface to avoid marring the same when advancing the stencil to a new position.

The sharpened ribs 14 at the marginal edges of the stencil openings enable the stencil to fit flatly against the wall, even though the block 15 mortar joints are not of uniform thickness.

Figures 1 and 2 illustrates the invention having the brick simulating openings 15 and 16 of a length greater than that of a standard brick, while Figure 4 illustrates a stencil 20 having its 20 openings 21 corresponding to the standard size brick.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A wall finishing stencil comprising a sheet metal frame of grating construction simulating the bricks and mortar joints of a brick wall, ribs on the rear surface of the frame matching the mortar joints of the wall, raised flanges at the upper edge and at one side edge of the frame

spacing the flanges from previously finished work, and a forwardly projecting flange at the other side edge of the frame stopping the spreading of finishing cement applied to the frame.

2. A wall finishing stencil comprising a sheet metal frame of grating construction simulating the bricks and mortar joints of a brick wall, ribs on the rear surface of the frame matching the mortar joints of the wall, raised flanges at the upper edge and at one side edge of the frame spacing the flanges from previously finished work, a handle on the upper flange, a stop pin adjacent the handle projecting rearwardly of the frame to prevent tilting of the upper edge of the frame, and a forwardly projecting flange at the other side of the frame stopping the spreading of finishing cement applied to the frame.

3. A wall finishing stencil comprising a sheet metal frame of grating construction and including horizontal and vertical bars simulating the mortar joints of a brick wall, ribs on the rear surface of the bars adapted for seating in the imitation mortar joints of a wall constructed of imitation brick building blocks, and marginal V-shaped ribs on the rear surface of the frame seating in mortar joints of the blocks for entering joints of various widths, said frame including openings representing courses of full and half bricks, the outer ends of said half brick openings of one course extending outwardly beyond the outer ends of the full brick openings of an adjacent course, and said V-shaped marginal rib being interrupted at the outer ends of the half brick openings.
